CONTROL OVERRIDE ASSEMBLY FOR RACING BOATS

Jack Davidson, 650 E. Hampton, Fresno, Calif. 93732

Filed Aug. 30, 1973, Ser. No. 393,010

Term of patent 14 years

Int. Cl. D12—06

U.S. Cl. D12—174

FIG. 1 is a top plan view of a control override assembly for racing boats.

FIG. 2 is a side elevation thereof.

FIG. 3 is a side elevation of the opposite side thereof.

FIG. 4 is a front elevation thereof.

FIG. 5 is a rear elevation thereof.

FIG. 6 is a bottom plan view thereof.

FIG. 7 is a perspective view thereof.

I claim:

The ornamental design for a control override assembly for racing boats, as shown.
